(57) **CLAIM**

The ornamental design for a stylus pen capable of expansion and contraction, as shown and described.

DESCRIPTION

FIG. 1 is a front, right and top perspective view of a stylus pen capable of expansion and contraction showing our new design in an expanded state;

FIG. 2 is a rear, left and bottom perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof;

FIG. 8 is a right side thereof;

FIG. 9 is a front, right and top perspective view of the stylus pen capable of expansion and contraction in a contracted state;

FIG. 10 is a rear, left and bottom perspective view thereof;

FIG. 11 is a front view thereof;

FIG. 12 is a rear view thereof;

FIG. 13 is a top plan view thereof;

FIG. 14 is a bottom plan view thereof;

FIG. 15 is a left side view thereof; and,

FIG. 16 is a right side thereof.
